UNITED STATES PATENT OFFICE

165,016

INTERCOMMUNICATING TELEPHONE MASTER STATION CABINET UNIT

Charles L. Metzler, Palisades Park, N. J., assignor to Dictograph Products Company, Inc., Jamaica, N. Y., a corporation of Delaware

Application June 23, 1951, Serial No. 15,646

Term of patent 7 years

(Cl. D26—14)

To all whom it may concern:

Be it known that I, Charles L. Metzler, a citizen of the United States and a resident of Palisades Park, county of Bergen, State of New Jersey, have invented a new, original, and ornamental Design for Intercommunicating Telephone Master Station Cabinet Unit, of which the following is a specification, reference being had to the accompanying drawing, forming a part hereof.

Fig. 1 is a front perspective view of the intercommunicating telephone master station cabinet unit, showing my new design; and

Fig. 2 is a side perspective view thereof.

The dominant features of my design reside in the portions shown in full lines. The back of the cabinet is substantially plain and the side opposite that shown in Fig. 2 appears the same as in Fig. 2 with the telephone and telephone bracket omitted.

I claim:

The ornamental design for an intercommunicating telephone master station cabinet unit, substantially as shown and described.

CHARLES L. METZLER.
